GLOVEBOX FOR HANDLING OBJECTS IN RADIO-ACTIVE ATMOSPHERES

Paul Farcy and Serge Sayen, Paris, France, assignors to
Commissariat à l'Energie Atomique, Paris (Seine),
France

Filed Jan. 4, 1960, Ser. No. 58,909

Term of patent 14 years

Claims priority, application France July 2, 1959

(Cl. D16—2)

FIG. 1 is a front perspective view taken from the left side of a glovebox for handling objects in radio-active atmospheres embodying our new design; and

FIG. 2 is a rear perspective view taken from the right side thereof.

The dominant features of our design reside in the full-line portions of the drawing.

We claim:

The ornamental design for a glovebox for handling objects in radio-active atmospheres, as shown and described.
